UNITED STATES PATENT OFFICE.

ROBERT P. GARSED, OF NORRISTOWN, PENNSYLVANIA.

ELEVATOR SIGNALING APPARATUS.

SPECIFICATION forming part of Letters Patent No. 441,150, dated November 25, 1890.

Application filed May 6, 1890. Serial No. 350,829. (No model.)

To all whom it may concern:

Be it known that I, ROBERT P. GARSED, a citizen of the United States, residing at Norristown, in the county of Montgomery and State of Pennsylvania, have invented new and useful Improvements in Elevator Signaling Apparatus, of which the following is a specification, reference being had to the accompanying drawings to more fully set forth the improvements.

The object of my invention is to provide a simple means of attaching a signal-actuating lever or other operative device to the wire cage of an elevator-shaft, as well as providing means for holding in place the conductors leading to annunciators connected with elevator-cars working within such shafts, my improvements being applicable as well for electricity or air as the actuating-motor.

The invention relates as well to means of retaining firmly in place the cut ends of wires in the edges of openings in the cage in which the actuating-levers are placed.

Figure 1 represents a front elevation, partly sectional, showing floor plan and general apparatus of an elevator with annunciator in place. Fig. 2 is a front elevation of an actuating-lever air-pump in place on a part of elevator-cage. Fig. 3 is a side view of the same.

Fig. 4 shows a front elevation of an air-pump with push-lever for its operation. Fig. 5 is a side view of the same. Fig. 6 is a transverse section of a cable or conductor supporting cleat. Fig. 7 is a perspective view of the same. Fig. 8 is a perspective view of a textile hose inclosing annunciator-conductors and held in place by an ordinary pipe strap or clamp. Fig. 9 is a front elevation of part of cage with pump removed, showing the ends of overlapping cut wires. Fig. 10 shows a part of a square mesh wire cage with the place of the back part of the push-lever or operating device illustrated by dotted lines. Fig. 11 is a detached perspective view of strap or clamp and casing, tube, or hose with split end for holding it to the wall of elevator-shaft. Fig. 12 is a modified form of Fig. 11. Fig. 13 is a preferred form of conductor-supporting brackets, and is well suited for short-distance conductors. Fig. 14 is a side elevation of actuating-lever, applicable to an electrical system of operation. Fig. 15 is a front

elevation of a supporting-rack for long-distance conductors.

A, Fig. 1, represents an elevato

55

B is the wall of the elevator-shaft.

C represents any floor of a building to which by the usual process an elevator is made to go.

D are the actuating-levers or pumps placed in a suitable position on each floor, and serve 60 as an element in operating the annunciator E within the elevator.

F is a cable, and is preferably an ordinary hose of suitable size inclosing the conductors G, said conductors at first being bunched together at their ends and so held while being put within the hose by one end of a twine used in drawing them through such hose to a length required to allow the elevator to ascend and descend.

70 H is a conductor-supporting cleat, and when in place on the wall of an elevator-shaft should be slanting to overcome the liability of the conductors G closing and preventing the passage of air, which they are apt to do when of considerable length, and consequently weighty.

D' is an inner clamping-plate with central part cut out, as shown in Figs. 9 and 10, and serves to hold, with the screws shown in Figs. 80 2 and 4, the actuating-lever plate in place, as well as to keep the parts of the wire cage firmly in position.

I is an ordinary clamp or strap, and serves 85 when in place to keep the cut end of hose F open, as well as securing it in place when used in holding the conductors G.

J is a flanged and flared conductor-supporting bracket, and when placed in the shaft of an elevator is supported by screws through 90 holes in the flange shown. This device is mostly used with its flange turned facing the side.

K is a flexible inflatable body having its outlet-tube L at its top center.

95 The operation of the device pneumatically is as follows: The actuating-lever D being operated upon any floor, the flexible body K is compressed and air is forced through the pipe leading from that floor to the annunciator 100 within the elevator, and by any of the well-known ways the attention of a proper person is called to the floor from whence the call has come.

To operate by electricity, the movement of the actuating-lever D, shown in Fig. 14, it will be seen, will produce the same result through any electric system—for instance, 5 that of A. Hahl, No. 148,447, March 10, 1874, electric indicators for elevators.

I do not claim novelty in many of the parts herein shown, as in my patents, No. 242,297, May 31, 1881, and No. 264,273, September 12, 10 1882, I show a clamp supporting a barrel or pipe, and in my patents No. 268,882, December 12, 1882, and No. 299,636, June 3, 1884, I show a flexible tube joined to a metal tube; and so with textile casing as an outside flexible support for conductors or air-pipes, the 15 same has been used for many years to my knowledge, and also the rubber tubing with textile covering, as mentioned in patent to Mayall, November 29, 1859, No. 26,276, has 20 for many years been used, it being understood that with elevator-annunciators metal pipe or electric conductors are generally used in a fixed position from the floors to a center point in height of shaft, and from thence 25 flexible tubing or conductors are used in a loose and suspended position of sufficient length to rise and fall with the elevator, and the practice has always been to incase this tubing or these conductors that are used in 30 this suspended position in non-stretching hose, that the strain incident to their weight may fall upon such hose, which is preferably textile, as, for a single instance, in the building of Messrs. Strawbridge & Clothier, Philadelphia, where I have the improvement here 35 set forth. They have had since 1879 textile hose covering the conductors leading to annunciators in their elevators.

Where there are many floors and great 40 length of tubing is required, it is best not to bunch such tubing, as the upper layers pressing upon the lower ones by the weight of the suspended part, such lower layers are apt

to get closed up and interfere with the operation of the device. To overcome this result 45 I run such tubing singly and use the form of supporting-bracket shown in Fig. 15, the several flared projections each supporting a conductor. Heretofore there has been more or less trouble in fastening actuating-levers to 50 the cages of elevators, wire ties being used as a general thing to support them on the outside of such cages. The advantages of my device will be apparent, also, in that it keeps the cut ends of wire in place. 55

Having thus described my invention, what I claim as new, and desire to secure by Letters Patent, is—

1. The combination, in a signaling apparatus, of the actuating-lever D, having a front 60 plate and supporting-screw, and a rear plate D', suitably shaped to receive the parts of such actuating-lever and allow of their movement, a meshed wire cage interposed between such lever-plates, a conductor G, attached to 65 and leading from such lever, and a flanged and flared supporting-bracket for the conductors G, and an annunciator adapted to be operated by the movement of said lever, substantially as and for the purposes set forth. 70

2. The combination, in an elevator signaling apparatus, of an elevator A, having an annunciator E attached to it, a series of flexible conductors leading from such annunciator to the fastening-point upon the wall of 75 the shaft of such elevator, and from thence in a suitable way to actuating devices upon the floors C, a supporting-bracket J, having a flange with holes for attachment thereon and a flared and channeled part or parts for 80 holding the conductors G in place, substantially as and for the purposes set forth.

R. P. Garsed.
